U.S. Cl. D56—1 A

Fig. 2

Fig. 3

FIG. 1 is a face view of a stringed musical instrument, specifically, a semi-fretted Ukrainian bandura, showing my new design;

FIG. 2 is a left side elevational view; and

FIG. 3 is a right side elevational view thereof.

The strings have been omitted from FIGS. 2 and 3 for convenience in illustration.

Portions of the drawings are shaded to indicate contrast in appearance.

I claim:

The ornamental design for a stringed musical instrument, as shown and described.
